UNITED STATES PATENT OFFICE.

SOLON CONKLIN, OF KIRKWOOD, NEW YORK.

IMPROVEMENT IN WASHING AND WRINGING MACHINES COMBINED.

Specification forming part of Letters Patent No. 122,441, dated January 2, 1872.

SPECIFICATION.

I, SOLON CONKLIN, of Kirkwood, in the county of Broome and State of New York, have invented certain Improvements in a Combined Washing and Wringing Machine for which Letters Patent No. 114,462, dated May 2, 1871, were granted to Jessie H. Murray, of which improvements the following is a specification, reference being had to the accompanying drawing, which is a perspective view of my machine.

The invention relates to that class of combined washing and wringing machines in which three rollers are used, of which two—that is, the upper one and the lower one—are mounted in movable bearings and are held in close contact with a third intermediate roller, whose bearings are not movable, and which is usually employed to drive the other two, its shaft being provided with a crank through which power may be applied. The invention consists in a novel combination and arrangement of three rollers and their actuating springs, as will be fully explained.

In the drawing my machine is represented as applied to a suitable tub, the side of which is broken away in order to more fully show the devices. The frame consists of two end pieces, B, bottom girts B¹, (one upon each side,) and top girt B². E is the central roller, its shaft having a crank, E', upon one end, as shown. D is the washing-roller. Its shaft is mounted in vertical slots b, and is therefore free to rise and fall within certain limits. By preference this roller is made with a fluted surface. A A are tongue-springs secured to the upper side of girt B². Their free ends project beyond the end pieces B and are connected with the shaft of roller D by means of rods a, the upper ends of said rods being threaded and provided with thumb-nuts C, whereby the tension of springs

A may be increased and roller D pressed against roller E with any desired force. D¹ is the wringing-roller. It, too, is mounted in slots or in movable bearings, and is held against roller E by a bar-spring, D², the pressure being regulated by a set-screw, d, working in a thread in girt B².

Although springs A A are practically two independent springs, yet for convenience I usually make them in one piece, as shown.

In practice I usually employ a supplemental roller, F, over which the articles pass as they go through between the wringing-roller D¹ and roller E, this arrangement serving to keep said articles from contact with roller D, which is apt to be wet.

I prefer to make roller E of rubber, as I find that the clothes are more readily freed from dirt by the action of the fluted roller D against an elastic one than against an unyielding one.

It will, of course, be understood that the springs A A and D² enable rollers D and D¹ to yield so as to allow any desired thickness of goods to be passed through by the action of roller E operated by the crank.

I do not claim, broadly, the combination of the three rollers D D¹ and E; nor do I claim, broadly, applying the pressure to the lower roller by means of the side rods a; but

What I do claim is—

The herein-described combined washing and wringing machine, consisting of the rollers D D¹ E, springs A A D², rods a, adjusting-screws C d, and crank E', these parts being combined and arranged for joint operation substantially as set forth.

SOLON CONKLIN.
